(57) **CLAIM**

The ornamental design for a clothesline recycling box, as shown and described.

DESCRIPTION

FIG. 1 is a front, right and top perspective view of a clothesline recycling box, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the clothesline recycling box in open state; and,

FIG. 10 is a front view of the clothesline recycling box in open state.

The broken lines shown in the drawings illustrate portions of the clothesline recycling box that form no part of the claimed design.

1 Claim, 10 Drawing Sheets
